UNITED STATES PATENT OFFICE.

HENDERSON E. W. LOOMIS, OF DUMONT, IOWA.

APPARATUS FOR SHARPENING LAWN-MOWERS.

No. 884,672.

Specification of Letters Patent.

Patented April 14, 1908.

Application filed October 24, 1907. Serial No. 398,985

To all whom it may concern:

Be it known that I, HENDERSON E. W. LOOMIS, a citizen of the United States, residing at Dumont, in the county of Butler and 5 State of Iowa, have invented a new and useful Apparatus for Sharpening Lawn-Mowers, of which the following is a specification:

This invention relates to mechanism for sharpening lawn-mowers and more particularly to a driving device for rotating the cutting blades of the mower when sharpening the same.

The object of the invention is to provide a comparatively simple and inexpensive device of the character described especially designed for attachment to one of the traction wheels of a mower and by means of which the cutting blades may be readily sharpened without the necessity of detaching the individual blades.

A further object is to provide a driving device including an expansible clamping member or strap capable of being quickly attached to or removed from the traction wheel of a 25 mower and which may be readily adjusted to fit traction wheels of different sizes.

A still further object of the invention is to generally improve this class of devices so as to increase their utility, durability and efficiency.

Further objects and advantages will appear in the following description, it being understood that various changes in form, proportions and minor details of construction 35 may be resorted to within the scope of the appended claims.

In the accompanying drawings forming a part of this specification: Figure 1 is a side elevation of a lawn-mower provided with a 40 driving device constructed in accordance with my invention. Fig. 2 is an enlarged detail sectional view of a portion of the driving device detached. Fig. 3 is a top plan view of the clamping mechanism. Fig. 4 is 45 a detail perspective view of the overlapped portions of the clamping band or strap.

Similar numerals of reference indicate corresponding parts in all of the figures of the drawings.

50 The improved driving device forming the subject matter of the present invention is principally designed for attachment to the traction wheel of a lawn-mower and by way of illustration is shown in position on a 55 lawn-mower of the ordinary construction in

which 5 designates one of the traction wheels, 6 the rotary cutting blades and 7 the handle.

The attachment consists of spaced brackets 8 and 9 to which is attached an expansible clamping band or strap 10 preferably 60 formed of spring metal and adapted to engage the periphery of the traction wheel 5, as shown. The bracket 8 is provided with an elongated slot 11 intersected by a transverse bar 12 which forms a support for the 65 adjacent portion of the clamping band 10, the end of the band 10 at the bar 12 being bent upon itself and the terminals thereof provided with laterally extending ears 13 which bear against the body of the strap and 70 serve to prevent slipping of the same. The bracket 9 is also provided with an elongated slot or opening 14 the end wall of which engages the opposite end of the strap or band. The metal forming the strap or band is bent 75 upon itself at the end wall of the slot 14 and the terminal bent to produce laterally extending ears 15 similar in construction to the ears 13. Engaging the strap between the ears 15 and the bracket 9 is a buckle 16 80 having an intermediate transverse bar 17 and over which is passed the superposed layers of the strap. It will thus be seen that by drawing the strap through the buckle 16 said strap may be adjusted to fit traction 85 wheels of different sizes. It will also be noted that the lower face of the brackets 8 and 9 as well as the lower face of the buckle 8 are formed with seating recesses or 90 depressions 18 for the reception of the strap or band so as to permit the strap or band to snugly engage the peripheral edge of the mower wheel.

The bracket 8 is formed with an enlargement 95 19 having a longitudinal bore or opening 20 formed therein for the reception of a bolt 21 one end of which extends through the perforated lug 22 on the bracket 9, while the opposite end thereof is provided with a clamping nut 23, there being a spring 24 interposed between the lug 22 and the enlargement 19 for expanding the band when the bolt 21 is released. The enlargement 19 is formed with a terminal shoulder 25 which engages the nut 23, the latter being preferably curved to conform to the shape of the enlargement and provided with an extended lip 26 which bears against the base of the bracket 8 and serves to lock said nut against 100 accidental rotation.

Extending laterally from the bracket 8 is an integral pin or stud upon which is mounted for rotation an operating handle 27 and by means of which the clamping band together with the traction wheel may be rotated when sharpening the cutting blades 6.

In operation the clamping band is adjusted to fit the traction wheel of the mower to be sharpened and said band placed in position 10 on the peripheral edge of the traction wheel and clamped in position thereon by adjusting the bolt 21. The handle 27 is then rotated which revolves the wheel together with the cutting blades 6 so that the latter are successively 15 brought in contact with the sharpening device, a conventional form of which is indicated at 28.

In order to remove the clamping band it is merely necessary to adjust the bolt 21 longitudinally 20 when the spring 24 will separate the brackets 8 and 9 and permit the clamping band to be readily detached from the traction wheel of the mower.

From the foregoing description it will be seen that there is provided an extremely simple, inexpensive and efficient device admirably adapted for the attainment of the ends in view.

Having thus described the invention what 30 is claimed is:

1. An attachment for lawn-mowers comprising spaced brackets one of which is provided with a perforated lug and the other with an enlargement forming a shoulder, 35 there being a longitudinal bore formed in the enlargement and piercing the stop shoulder, a clamping band engaging the brackets and adapted to engage the traction wheel of the lawn mower, a bolt extended through the 40 perforation in the lug and the bore of the

enlargement and provided with terminal threads, a nut threaded on the bolt and bearing against the shoulder, a spring surrounding the bolt and interposed between the lug and enlargement, and an operating handle 45 extending laterally from one of the brackets.

2. An attachment for lawn-mowers comprising spaced brackets having their lower faces formed with seating recesses, an adjustable clamping band engaging the opposite ends of the brackets and seated in said recesses, said band being adapted to engage the traction wheel of the lawn-mower, a buckle carried by the band and provided with seating recesses for the reception of the band, 55 and means connecting the brackets for clamping the band in engagement with the traction wheel.

3. An attachment for lawn-mowers comprising spaced brackets, an adjustable clamp- 60 ing band having one end thereof secured to the adjacent bracket and its terminal portion provided with laterally extending ears folded laterally on said band, the opposite end of the band being secured to the mating bracket and provided with similar ears, a buckle carried by the band for locking the latter in adjusted position, means connecting the brackets for clamping the band in position on the traction wheel of the mower, and 65 a handle extending laterally from one of said brackets.

In testimony that I claim the foregoing as my own, I have hereto affixed my signature in the presence of two witnesses.

HENDERSON E. W. LOOMIS.
